LOCKER ROOM BENCH OR THE LIKE

Richard G. Reineman, Covina, Calif., and George E. Schaefer, Muskegon Heights, Mich., assignors to Brunswick Corporation, a corporation of Delaware

Filed Apr. 11, 1960, Ser. No. 60,125

Term of patent 14 years

(Cl. D15—11)

Fig. 1

Fig. 2

Fig. 3

Fig. 4

Fig. 5

Fig. 6

Fig. 1 is a top plan view of a locker room bench or the like showing our new design;

Fig. 2 is a side elevational view thereof;

Fig. 3 is an end elevational view thereof;

Fig. 4 is an enlarged fragmentary longitudinal sectional view at about the line 4—4 of Fig. 1;

Fig. 5 is an enlarged fragmentary transverse sectional view at about the line 5—5 of Fig. 1; and

Fig. 6 is a perspective view of the bench.

The opposite side and the opposite end from those shown are substantially identical to those shown.

We claim:

The ornamental design for a locker room bench or the like, as shown and described.
